STEAM PIPE CONNECTION FOR ARTICULATED LOCOMOTIVES

Filed Nov. 14, 1927 2 Sheets-Sheet 2

UNITED STATES PATENT OFFICE

REGINALD J. OFFUTT, OF KEYSER, WEST VIRGINIA, ASSIGNOR TO JOHNS-MANVILLE CORPORATION, OF NEW YORK, N. Y., A CORPORATION OF NEW YORK

STEAM-PIPE CONNECTION FOR ARTICULATED LOCOMOTIVES

Application filed November 14, 1927. Serial No. 232,983.

My invention relates to locomotive steam engines of the articulated type, in which one set of driving wheels and their journal-frame constitute a pilot truck on which one set of cylinders and their usual connections to driving wheels are mounted, the said pilot truck being laterally movable in relation to the engine boiler.

In such locomotive engines the steam-pipe, be it supply or exhaust, connecting the pilot truck cylinders to the boiler at the smoke-box end is so articulately constructed as to adapt itself to the relative alterations of position between the forward end of the boiler and the cylinders, and is, virtually, and is usually termed, flexible, although no portion of the steam connection is, strictly speaking, flexible. Two types of such adaptable or flexible steam connections have been employed, one having a packed ball-joint connection at each end, with a telescoping joint in the horizontal reach-member of the connection, another with a hanger pipe section and horizontal reach section, articulated by a packed ball-joint between the terminal ball-joints. The steam-pipes, whether feed or exhaust, which serve the forward cylinders on the pilot truck are necessarily adaptable to changes in positional relationship as between the pilot truck with the cylinders attached to its frame, and the boiler, its frame, and adjuncts such as the rear cylinders and steam chest which are attached to the main frame of the locomotive. Either form, by its flexibility as a whole, accommodates itself to the relative movements between the main frame of the locomotive and the pilot truck cylinders. Another example of a flexible, articulated and extensible, steam connection is furnished by the so-called "receiver steam-pipe", extending forward from the boiler frame cylinder system to the steam chest of the pilot truck frame cylinder system, wherein the pipe is ball-jointed to the rear cylinder system, rigidly connected to the forward cylinder system, and provided with a sliding sleeve joint between those two points of attachment.

The weight of such steam-pipe connections, and the frequent movements thereof as the locomotive engine runs, and the reactive

thrusts occasioned by the pressure and passage of steam contribute to put an undesirable burden on the ball-joint packings when the latter have to sustain all the occasioned stresses, and have been observed to shorten the useful life of such packings considerably.

My invention has for its principal objects the relief of these ball-joint packings from severe wearing conditions, and the automatic restoration of the flexible steam connection as a whole to approximately true central and vertical alignment when the locomotive engine passes from a curve to a straight section of railway track.

In the drawings hereto annexed, which illustrate my invention,

Fig. 1 shows, in longitudinal elevation, a telescope-joint type of flexible steam connection;

Fig. 2, a rear elevation of the rear or boiler end of the same;

Fig. 3, a front elevation of the cylinder end of the same;

Fig. 4, in longitudinal elevation, the rear portion of a three-ball type of flexible steam connection; and

Fig. 5, a vertical cross section at the line 5—5 of Fig. 4.

In Figs. 1, 2 and 3, the associated parts represented are as follows:

The lower plates, 1, of the smoke box at the forward end of the locomotive engine boiler; an elbow section, 2, of the flexible steam-pipe connection; a horizontal forwardly reaching section, 3, of the same connection; a suitably steam-packed telescoping joint, 4, in the said horizontal forwardly reaching portion; the forward elbow, 5, of the said steam connection; a flange casting, 23, forming part of the steam chest of the cylinders (which are mounted upon the forward or pilot truck of the articulated locomotive); the steam-packed ball-joint, 6, with which the elbow section 2 is articulated to the distributor of the boiler; the distributor D; the ball-joint, 7, with which the elbow section 5 is articulated to the steam chest casting 23; a bearing lug, 8, formed integrally with or secured to the elbow 2; a bearing stud, 8a, with preferably a rounded end, set

80

in the lug 8; a yoke, 9, provided with a bearing socket plate 9a which engages with the pin 8a; perforated horizontal extensions, 10, of the yoke 9; hook-ended hangers, 11, loosely passing through the extensions 10; suspension eye-bolts, 12, secured to the locomotive boiler structure at the smoke box end, said eye-bolts receiving the hooked ends of the hangers 11; springs, 13, held between the extensions 10 of the yoke 9 and the nut-adjustable abutments 14 on the lower ends of hangers 11.

The adjustable abutments 14 being set up, compress the springs 13 against the hanger-extensions 10 so that the load at and stresses on the rear end of the steam-pipe connection are sustained thereby yieldingly, and the ball-joint 6 with its packing is relieved of much of the burden which otherwise and heretofore has been borne thereby.

The above-described spring-suspension of the boiler end of the said flexible steam connection performs also the function of restoring said steam connection to substantially centered alignment when the locomotive passes from a curved to a straight section of track; for when the locomotive is running on a curve, and the flexible connection both swivels and rocks upon the ball-joint 6, the angular relationship of the hangers and their support, and the resultant of the compressive stresses of the springs 13 tends to and will restore the steam-pipe to its normal position as shown in the drawings when the locomotive passes to a straight section of track.

The spring suspension of the boiler end of the steam-pipe connection, above described, will perform the stated functions with substantial satisfactoriness even though the steam chest end of the said connection be left as heretofore, and without any supplementary adjuncts to the forward elbow 5 and to ball-joint connection 7. It is, however, considered desirable to provide a yoke and spring relieving attachment and alignment restoring device at the forward end also and this is illustrated in Figs. 1 and 3. Parts constituting said device are as follows:

50. A lug 15, formed on or secured to the upper part of the elbow 5, and a bearing pin 15a, mounted on the said lug; a yoke-bar 16 provided with a socket plate 16a (which cooperates with the bearing pin 15a); holding rods 17 hooked at their lower ends and passing loosely through holes in the yoke-bar 16; eye-bolts 18 which constitute studs, screw-anchored at the casting 23; spring buffers 19 held compressed between the nut-adjustable abutments 20; compression springs 21 surrounding the upper ends of the holding down rods 17 and held compressed between the upper ends of the yoke-bar 16 and the nut-adjustable abutments 22.

65. The confinement of the springs 21 under

compression exerts a properly adjusted amount of downward pressure upon the forward end of the elbow 5, which compensates for the reactive thrusts of steam against the bend of the elbow. The dimensional and positional relationships of the ball-joint, the rods and their end-attachments, and the yoke-bar are such that the forward elbow 5 will be restored to its normal vertical alignment whenever this alignment, after having been disturbed by the relative movement of the locomotive boiler and the pilot truck, is free to be resumed when the running locomotive engine returns to a straight section of track after having rounded a curve.

A mode of application of spring suspension to the boiler end of the 3-ball-joint type of flexible steam connection is illustrated in Figs. 4 and 5 wherein the cooperating parts are as follows: the vertical hanging section, 24, of the steam connection; the elbowed, forwardly-reaching, horizontal steam-pipe connection member 25; the ball-joint connection 26 with the steam distributor D; the ball-joint connection, 27, between the pipe-members 24 and 25 (the ball-joint connection with the cylinder system is not here shown); lugs, 28, formed on or otherwise secured (as by electric welding) to the pipe-member 25; eye-bolts, 29, secured in the smoke-box end of the locomotive boiler; the eyes, 30, of said bolts; springs, 31, hooked into the eyes 30; hooks, 32, with which the lower ends of the springs 31 engage and which pass through holes provided for the purpose in lugs 28; adjusting nuts, 33, on the hooks 32.

A suitable lifting tension of the springs 31 having been produced by means of the adjusting nuts 33, the weight load and reaction-shocks otherwise borne entirely by the packing in the ball-joint 26, are relieved. Whenever the positional relationship of the locomotive boiler with the pilot truck displaces the flexible steam connection from its normal, vertical and horizontal alignment, the spring hangers 31 are so angularly related with their support as to be differentially stressed in such manner that the flexible steam-pipe connection will be thereby restored to its normal vertical and horizontal alignment as soon as the boiler and pilot truck resume their alignment on running from a curve to a straight section of track.

I claim:

1. The combination, with a flexible steam connection of an articulated locomotive engine, of elastic stress-relieving means applied at a ball-joint packing end thereof to restore the connection to its normal condition.

2. The combination, with a flexible steam connection of an articulated locomotive engine, of elastic stress-relieving suspension means applied at a ball-joint packing end thereof to restore the connection to its normal condition.

3. The combination, with a flexible steam connection of an articulated locomotive engine, of elastic, pivotally mounted stress-relieving means applied at a ball-joint packing end thereof to restore the connection to its normal condition. 70
4. The combination, with a flexible steam connection of an articulated locomotive engine, of elastic, pivotally mounted stress-relieving suspension means applied at a ball-joint packing end thereof to restore the connection to its normal condition. 75
- 10 5. The combination, with a flexible steam connection of an articulated locomotive engine, of elastic stress-relieving means applied at either side of a ball-joint packing end thereof to restore the connection to its normal condition. 80
- 15 6. The combination, with a flexible steam connection of an articulated locomotive engine, of elastic stress-relieving suspension means applied at either side of a ball-joint packing end thereof to restore the connection to its normal condition. 85
- 20 25 7. The combination, with a flexible steam connection of an articulated locomotive engine, of elastic, pivotally mounted stress-relieving means applied at either side of a ball-joint packing end thereof to restore the connection to its normal condition. 90
- 30 35 8. The combination, with a flexible steam connection of an articulated locomotive engine, of elastic, pivotally mounted stress-relieving suspension means applied at either side of a ball-joint packing end thereof to restore the connection to its normal condition. 95
- 35 9. The combination in an articulated locomotive in which the boiler overhangs a frame 100
- 40 on which is mounted a cylinder structure, of a flexible steam pipe connected at one end to the boiler and at the other end to the cylinder structure, and springs located on opposite sides of each end of the pipe for yieldably holding the ends of the pipe in connection with the boiler and cylinder structure respectively. 105
- 45 10. The combination in an articulated locomotive in which the boiler overhangs a frame 110
- 50 on which is mounted a cylinder structure, of a flexible steam pipe connected at one end to the boiler and at the other end to the cylinder structure, and springs located on opposite sides of each end of the pipe for yieldably holding the ends of the pipe in connection with the boiler and cylinder structure respectively, the springs at one end of the pipe being attached to the boiler and the springs at the other end thereof being attached to the structure. 115
- 55 11. The combination in an articulated locomotive in which the boiler overhangs a frame 120
- 60 on which is mounted a cylinder structure, of a flexible steam pipe connected at one end to the boiler and at the other end to the cylinder structure, and springs located on opposite sides of each end of the pipe for yieldably holding the ends of the pipe in connection with the boiler and cylinder structure respectively, the springs each secured at one end to the pipe 125
- 65 12. The combination in an articulated locomotive in which the boiler overhangs a frame 130
- 70 on which is mounted a cylinder structure, of a flexible steam pipe connected at one end to the boiler and at the other end to the cylinder structure, said pipe having a vertical section at each end thereof and a horizontal section connecting said vertical sections and springs located on opposite sides of each vertical section for yieldably maintaining the ends of the vertical sections in connection with the boiler and cylinder structure respectively. 75
- 75 13. The combination in an articulated locomotive in which the boiler overhangs a frame 80
- 80 on which is mounted a cylinder structure, of a flexible steam pipe connected at one end to the boiler and at the other end to the cylinder structure, said pipe having a vertical section at each end thereof and a horizontal section connecting said vertical sections and springs located on opposite sides of each vertical section for yieldably maintaining the ends of the vertical sections in connection with the boiler and cylinder structure respectively, the springs associated with one vertical section being attached to the boiler and the springs associated with the other vertical section being attached to the cylinder structure. 85
- 85 14. The combination in an articulated locomotive in which the boiler overhangs a frame 90
- 90 on which is mounted a cylinder structure, of a flexible pipe for conducting steam between the boiler and the cylinder structure, ball and socket connections between the ends of the pipe and the boiler and cylinder structure respectively and yieldable means associated with the ball and socket connections for restoring the pipe to its normal relation to the boiler and cylinder structure when removed therefrom. 95
- 95 15. The combination in an articulated locomotive in which the boiler overhangs a frame 100
- 100 on which is mounted a cylinder structure, of a flexible pipe for conducting steam between the boiler and the cylinder structure, ball and socket connections between the ends of the pipe and the boiler and cylinder structure respectively and yieldable means associated with the ball and socket connections for restoring the pipe to its normal relation to the boiler and cylinder structure when removed therefrom, said yieldable means including springs each secured at one end to the pipe 105

and at the other end to the boiler or the cylinder structure.

16. The combination in an articulated locomotive in which the boiler overhangs a frame on which is mounted a cylinder structure, of a flexible pipe for conducting steam between the boiler and the cylinder structure, a ball and socket connection between the pipe and the boiler, the pipe at that end terminating in a vertical section, and yieldable means associated with the ball and socket connection for restoring the vertical section of the pipe to a position perpendicular to the boiler when removed therefrom.

17. The combination in an articulated locomotive in which the boiler overhangs a frame on which is mounted a cylinder structure, of a flexible pipe for conducting steam between the boiler and the cylinder structure, a ball and socket connection between the pipe and the boiler, the pipe at that end terminating in a vertical section, and yieldable means associated with the ball and socket connection for restoring the vertical section of the pipe to a position perpendicular to the boiler when removed therefrom, said yieldable means including a yoke upon which the vertical section rests and springs connected at one end to the yoke and at the other end to the boiler.

Signed by me at Denver, Colorado, this thirty-first day of October, 1927.
